(57) **CLAIM**

The ornamental design for a packaging container for small articles, as shown and described.

DESCRIPTION

FIG. 1 is a top, front, and right perspective view of a packaging container for small articles with its lid closed, showing my new design;

FIG. 2 is a top plan view of the same closed container;

FIG. 3 is a front view of the same closed container;

FIG. 4 is a bottom plan view of the same closed container;

FIG. 5 is a rear view of the same closed container;

FIG. 6 is a right side view of the same closed container, which is symmetrical to a left side view;

FIG. 7 is a sectional view of the same closed container taken along lines 7-7 in FIG. 2;

FIG. 8 is a sectional view of the same closed container taken along lines 8-8 in FIG. 3;

FIG. 9 is a top, front, and right perspective view of the same packaging container with its lid held open;

FIG. 10 is a top plan view of the same open container;

FIG. 11 is a front view of the same open container;

FIG. 12 is a bottom plan view of the same open container;

FIG. 13 is a rear view of the same open container;

FIG. 14 is a right side view of the same open container, which is symmetrical to a left side view;

FIG. 15 is a sectional view of the same open container taken along lines 15-15 in FIG. 10;

FIG. 16 is a sectional view of the same open container taken along lines 16-16 in FIG. 10; and,

FIG. 17 is a sectional view of the same open container taken along lines 17-17 in FIG. 11.

The broken lines in the figures are for illustrating portions of the article that form no part of the claimed design.

1 Claim, 10 Drawing Sheets
